UNITED STATES PATENT OFFICE

172,415

EXPANSIBLE CHAIN FOR A BRACELET OR THE LIKE

William C. Boots, Rumford, R. I., assignor to Foster Metal Products Incorporated, Attleboro, Mass., a corporation of Massachusetts

Application December 4, 1953, Serial No. 27,917

Term of patent 14 years

(Cl. D45—4)

To all whom it may concern:

Be it known that I, William C. Boots, a citizen of the United States, residing at Rumford, in the county of Providence and State of Rhode Island, have invented a new, original, and ornamental Design for an Expansible Chain for a Bracelet or the like, of which the following is a specification, reference being had to the accompanying drawing, forming a part thereof, in which:

Fig. 1 is a plan view of a portion of an expansible chain for a bracelet or the like, showing my new design,

Fig. 2 is a similar view showing the chain in expanded condition,

Fig. 3 is a perspective view of one of the convex links of Fig. 1 drawn on an enlarged scale, and

Fig. 4 is a perspective view of one of the concave links of Fig. 1 drawn on an enlarged scale.

I claim:

The ornamental design for an expansible chain for a bracelet or the like, substantially as shown.
